UNITED STATES PATENT OFFICE.

LONZO L. CLIPPINGER, OF EVERETT, WASHINGTON.

CLEANING DEVICE FOR BOOTS AND SHOES.

1,149,729.

Specification of Letters Patent. Patented Aug. 10, 1915.

Application filed April 17, 1914. Serial No. 832,578.

To all whom it may concern:

Be it known that I, LONZO L. CLIPPINGER, a citizen of the United States, residing at Everett, in the county of Snohomish and State of Washington, have invented new and useful Improvements in Cleaning Devices for Boots and Shoes, of which the following is a specification.

This invention relates to improvements in cleaning devices for boots, shoes and the like and has particular application to a floor supported device of this character.

In carrying out the present invention, it is my purpose to provide a cleaning device for boots and shoes which will embody among other features a bottom brush and side brushes disposed at the opposite sides of the bottom brush and at right angles thereto and connected with the latter in such manner as to adapt themselves to shoes of various widths whereby when a shoe is drawn through the device the bottom brush will clean the bottom thereof while the side brushes will act upon the sides of the shoe to remove the dirt therefrom, such side brushes moving relatively to the bottom brush to accommodate the shoe. It is also my purpose to provide a device of the class described wherein the various brushes will be held assembled and secured to the floor in such manner that the device as an entirety may be swung to inactive position to facilitate the cleaning of the floor and the device.

With the above and other objects in view, the invention consists in the construction, combination and arrangement of parts hereinafter set forth in and falling within the scope of the claims.

In the accompanying drawing; Figure 1 is a perspective view of a cleaning device constructed in accordance with the present invention. Fig. 2 is a view in elevation showing the device in inactive position.

Referring now to the drawing in detail, 1 designates a support composed, in the present instance, of a single length of wire bent upon itself intermediate its ends as at 2 to provide parallel arms 3 which, in turn, are bent at right angles to themselves and projected in opposite directions as at 4 to form connecting limbs 5, the latter being bent at right angles to themselves as at 6 and lying in planes substantially parallel with the arms 3 at the opposite sides of the latter and forming supporting arms 7. Each arm 7,

adjacent to the junction of the same with the connecting member 5 is coiled upon itself to form a spring 8.

Fastened to the arms 3 in some suitable manner is a bottom brush 9 normally lying in a horizontal plane and having the bristles thereof projecting upwardly, while secured to the supporting arms 7, 7 at the opposite sides of the brush 9 are side brushes 10, 10 arranged at right angles to the bottom brush and having the bristles thereof confronting each other as illustrated in Fig. 1.

In practice, the connecting members 5 of the support are secured to the floor or other support by means of straps 11, 11, such straps permitting the swinging of the device as an entirety so that the brushes may be disposed in a horizontal plane and in a vertical plane. Normally, the device lies in a horizontal plane and when it is desired to remove the dirt from the shoe, the latter is placed within the brushes 10 and upon the bottom brush 9 and drawn through the device longitudinally of the brushes whereby the bristles act upon the bottom and sides of the shoe to effectively clean the latter. The springs 8 in the supporting arms 7 permit the side brushes to swing relatively to the bottom brush so that the device will receive shoes of various widths, the springs holding the confronting faces of the brushes in frictional engagement with the side of the shoe in the use of the device.

It will be seen that the support acts to hold the brushes in proper relative positions and at the same time permits the device to be swung as an entirety from an active position to an inactive position and vice versa.

While I have herein shown and described one preferred form of my invention by way of illustration, I wish it to be understood that I do not limit or confine myself to the precise details of construction herein described and delineated, as modification and variation may be made within the scope of the claims without departing from the spirit of the invention.

I claim:

1. A shoe cleaning device comprising a bottom brush, side brushes and a support holding said brushes assembled and comprising a single length of wire bent upon itself intermediate its ends to form supporting arms and then extended laterally to provide connecting limbs and thence bent at right angles to form supporting arms lying

- in parallel planes with the first arm at the opposite sides of the latter, and connections between said first arms and bottom brush and said last arms and side brushes.
- 5 2. A shoe cleaning device comprising a bottom brush, side brushes and a support holding said brushes assembled and comprising a single length of wire bent upon itself intermediate its ends to form supporting arms and then extended laterally to provide connecting limbs and thence bent at right angles to form supporting arms lying in parallel planes with the first arm at the
- 10

opposite sides of the latter, and connections between said first arms and bottom brush 15 and said last arms and side brushes, said last arms being coiled upon themselves to form springs whereby the side brushes may move relatively to the bottom brush.

In testimony whereof I affix my signature 20 in presence of two witnesses.

LONZO L. CLIPPINGER.
